UNITED STATES PATENT OFFICE.

FAY O. FARWELL, OF DUBUQUE, IOWA, ASSIGNOR TO THE ADAMS COMPANY, OF SAME PLACE.

DESIGN FOR A STOVEPIPE-SHELF.

SPECIFICATION forming part of Design No. 25,809, dated July 21, 1896.

Application filed May 18, 1896. Serial No. 592,089. Term of patent 3½ years.

To all whom it may concern:

Be it known that I, FAY O. FARWELL, a citizen of the United States, residing in Dubuque, county of Dubuque and State of Iowa, 5 have invented and produced a new and original Design for a Stovepipe-Shelf, of which the following is a specification.

My invention relates to designs for stovepipe-shelves, and the essential feature thereof 10 consists in the novel contour or configuration of the shelf. The shelf is made in the form of a rectangle with an open semicircle formed in one side with a border around the shelf, and the shelf within the border ornamented 15 by scroll or netting work, all of which will be fully described in the following specification and illustrated in the accompanying drawing, forming a part hereof, in which the figure represents a shelf made in accordance with my improved design.

Referring to the drawing, A represents the band or border around the shelf. It will be

seen that this border has in it six right angles at a, b, and c. Three sides of the rectangle are at right angles to each other, and the 25 fourth side extends from opposite corners at b, about one-third across from each side at c c, and then at right angles at c for a short distance. These ends e are then united by a semicircle B. In this consists the peculiar 30 contour of my design. Within the border A is any suitable scrollwork or ornamentation.

In practice when a shelf constructed as here shown and described is attached to the stovepipe it is both novel and ornamental. 35

What I claim is—

A design for stovepipe-shelves substantially as shown and described.

In testimony whereof I affix my signature in the presence of two witnesses.

FAY O. FARWELL.
